Primary Examiner — Paula Allen Greene(74) *Attorney, Agent, or Firm* — Haug Partners LLP(57) **CLAIM**

The ornamental design for a headset, as shown and described.

DESCRIPTION

FIG. 1 is a perspective view of headphones showing my new design;

FIG. 2 is a right side view of headphones thereof;

FIG. 3 is a left side view of headphones thereof;

FIG. 4 is a rear view of headphones thereof;

FIG. 5 is a front view of headphones thereof;

FIG. 6 is a bottom side view of headphones thereof; and,

FIG. 7 is a top side view of headphones thereof.

The broken lines in the figures depict environmental that forms no part of the claimed design.
